UNITED STATES PATENT OFFICE.

ARTHUR H. WESTON, OF ROLAND PARK, MARYLAND.

SHOE-BLACKING STAND.

No. 905,258.

Specification of Letters Patent.

Patented Dec. 1, 1908.

Application filed January 27, 1908. Serial No. 412,860.

To all whom it may concern:

Be it known that I, ARTHUR H. WESTON, citizen of the United States of America, residing at Roland Park, Baltimore county, Maryland, have invented certain new and useful Improvements in Shoe-Blacking Stands, of which the following is a specification.

The present invention relates to a shoe clamp and more particularly to that type of clamp, one member of which acts as a rest to support the foot and the shoe thereon while the latter is being polished, cleaned or repaired.

The clamp to be described is particularly adapted to the use to which it is applied, in that it is automatically locked and adjusted to any size of shoe. It grips the shoe securely and is easily disengaged. It consists of few parts which may be cheaply manufactured and of such proportions as to be strong and durable.

My device consists of a suitable frame, a foot plate, a carrier mounted to move in a predetermined path in relation thereto, a jaw lever pivoted thereon, a locking surface adapted to coöperate with the jaw and lock it when it engages the article to be clamped and means for moving the carriage to press the jaws against the shoe.

An important feature of my invention is the locking jaw lever and locking surface, so arranged that when the jaw is advanced against a resistance, it is locked in each new position which it occupies and cannot be withdrawn until unlocked by reversal of the actuating means. The number of positions in its path in which the jaw may be locked is unlimited, so that the resulting pressure on the shoe is determined by the force applied to the actuating lever and not by the size of the particular shoe.

The drawings illustrate my invention.

Figure 1, is a side elevation of my device, Fig. 2, an enlarged fragmentary elevation partly in section. Fig. 3, a perspective of the jaw lever and carrier. Fig. 4 is a section on line 4—4, Fig. 2.

The shoe blacking stand consists of a frame 1 consisting of an upright web 2, a base 3 and a foot plate 4. The foot plate is shaped to support a shoe of any usual size and is chambered at the rear at 5 to receive the heel. The forward wall 6 of the chamber forms an abutment against which the heel rests and acts as the fixed jaw of the clamp which is to be described. Below the

heel plate and substantially parallel to the same, the web is provided with ways 7, one on each side of the web. The carrier 8 consists of parallel uprights 9 joined by a horizontal cross bar 10. Each upright is provided with a forwardly extending follower bar 11. These follower bars are parallel to each other and adapted to engage and slide in the ways 7. The jaw lever 12 is provided at one end with a jaw 13 adapted to engage the heel of the shoe at the rear and at its opposite extremity with a downwardly disposed locking surface 14. This lever is provided with a transversely extending pivot at 15 a point intermediate of its length. This pivot engages suitable journal bearings in the upper extremities of the uprights 9, so that the jaw lever swings between the latter with the jaw up and forwardly disposed. The web 2 is provided intermediate the ways 7 with a locking member 15 which extends to the rear parallel to the ways. This locking member is in the form of a straight bar, its upper surface 16 is flat and will be hereinafter termed a locking surface. When the followers 11 engage the ways 7, the locking member 15 extends to the rear between the uprights 9 above the cross bar 10 and below the locking lever 12. The least radius of the locking surface 14 of the jaw lever, measured from the center 23 about which that lever turns, is just equal to the distance from the center 23 to the locking surface 16 of the member 15. An actuating lever 17 provided intermediately of its length with a transverse pivot 18 is mounted in suitable journal bearings 19 on the frame below the rear portion of the ways. The upper extremity of this lever is slotted at 20 to receive the transverse pin 21 which is mounted in the lower extremities 22 of the uprights 9, extending from one to the other. The lower extremity of the lever 17 is adapted to be manually engaged.

In the operation of my device, the shoe, preferably on the foot, is placed on the foot plate 4 with the heel in the heel chamber 5 and pressed against the abutment 6. The lower extremity of the lever 17 is pressed to the rear, rotating the lever about its center 18, whereby the carrier 8 is moved forward, the followers 11 sliding in the ways 7. The jaw 13 is brought into contact with the rear of the heel and rotated about its center 23. This rotation of the jaw lever brings the locking surface 14 into contact with the

- locking surface 16 of the frame. In this connection it should be noted that the radius of the surface 14 of the lever measured from the center 23 increases in a direction opposite to that of the rotation just described. Increased pressure on the long arm of the lever 17 forces the locking surface of the lever into closer contact with the locking surface of the frame and the two members 10 become clamped in this position. The resistance offered to backward pressure applied to the jaw increases with that pressure. To release the shoe, forward pressure is applied to the lower arm of the lever 17. 15 The carrier 8 moves to the rear with but slight resistance, unlocking the lever 12.
- Having thus described my invention, what I claim and desire to secure by Letters Patent is:
- 20 1. In a stand for blacking shoes, in combination, a support for the shoe having a locking surface, an abutment, a carrier mounted on the support to move in a fixed path, a jaw member mounted on the carrier 25 to move in a fixed path relatively thereto, and means for advancing the carrier to press one end of the jaw member against the shoe and the other end against the locking surface.
- 20 2. In a stand for blacking shoes in combination, a support for the shoe having a plane locking surface, an abutment on the support, a carrier mounted on the support to move in a fixed path relatively thereto, a 35 jaw lever pivotally mounted on the carrier and means for advancing the carrier to press one end of the jaw lever against the shoe and clamp the other end against the locking surface.
- 40 3. In a shoe clamp, a support for the shoe having a plane locking surface, an abutment

on the support, a carrier mounted on the support to move in a fixed path relatively thereto, a lever pivotally mounted on the carrier having a jaw and a locking surface 45 and means for advancing the carrier to press the jaw against the shoe and the locking surface of the lever against the locking surface of the support.

4. In a shoe clamp, in combination, a support for the shoe, an abutment on the support to prevent forward movement of the shoe, a carrier mounted on the support to slide in a fixed path, a jaw member pivotally mounted on the carrier, the jaw member having a jaw and a locking surface, the radius of the locking surface of the jaw member, measured from the pivot, increasing in a direction opposite to that of the rotation caused by pressure of the shoe against the jaw, a 60 locking member on the support having a plane locking surface, and means for advancing the carrier to press the jaw against the shoe and the locking surface of the jaw member against the locking surface of the 65 support.

5. In a shoe clamp, a support for the shoe, a carrier, a jaw lever pivotally mounted on the carrier, an abutment, a locking member on the support having a uniform locking surface and means for advancing the carrier against a resistance, whereby the jaw lever is made to coöperate with the locking surface and become locked against rearward movement in any position in which it meets 70 the resistance.

Signed by me at Baltimore, Maryland this 24th day of January 1908.

ARTHUR H. WESTON.
